UNITED STATES PATENT OFFICE.

JOSEPH FOURNIER, OF CENTRAL FALLS, RHODE ISLAND.

BOBBIN HOLDER.

Application filed December 5, 1922. Serial No. 605,101.

To all whom it may concern:

Be it known that I, JOSEPH FOURNIER, a citizen of the United States, residing at 23 Fletcher Street, Central Falls, in the county of Providence and State of Rhode Island, have invented certain new and useful Improvements in Bobbin Holders, of which the following is a specification.

My invention relates to improvements in bobbin holders such as are used for spooling, doubling, and other similar machines, and the purpose of my invention is to provide a holder that will prevent the detachment of the bobbin from its bed by the draft on the thread or yarn and also to provide for bobbins of different lengths in the same machine. My invention consists substantially of a series of V-shaped troughs in which the bobbins are placed horizontally; and hoods approximately semi-circular in form covering the bobbins at each end thereof, the hoods at one end of the bobbins being capable of being turned backward upon suitable hinges and having a locking device to hold them in place when over the bobbins.

Another feature of my invention is an adjustable member by which bobbins of different lengths can be accommodated in the same holders and which can be quickly adjusted to bobbins of different lengths.

These purposes and objects are accomplished by the device shown in the accompanying drawing, in which—

Figure 1 is a vertical view of one end of a bobbin together with the hinged plate and the locking device for holding said plate in place while the machine is in operation.

Figure 2, a vertical view of the same portion of my device at right angles to that shown in Figure 1;

Figure 3, a vertical view of the opposite end of the bobbin from that shown in Figure 1;

Figure 4, a plan view of a portion of my device with bobbins enclosed;

Figure 5, a sectional view through A—A of Figure 1.

The same parts are indicated by the same numerals throughout the various views.

In Figure 1, 4—8 represents the bobbin of yarn or thread; 1, the wooden base on which the holder is mounted, consisting of an ordinary board of suitable width and length; 9 is an end-piece, preferably of thin metal, hinged to 1 by means of the hinges 2 and capable of being laid back in a quarter

circle, as shown by the dotted lines in Figure 1. Fixed upon the end-piece 9 and at right angles thereto is the wing 3, while attached to the base 1, (see Figure 2) is the bed 6—6' composed of thin metal, having a plurality of V-shaped troughs 6' in which the bobbin 8 is placed and retained by gravity. Fixed upon 6 is the spring member 7 which serves as a locking device for the wing 3. The operation of this locking device is disclosed more clearly by Figure 2. The lower edge of the wing member 3 is provided with a bead or enlarged portion and the shape of the locking member 7 is such as to admit the insertion of this bead between 7 and the vertical member 6 and by the spring tension of the member 7 hold securely the member 9 in the position shown by the full lines in Figure 1, and at the same time permit of the release of the end-piece 9 with the wing 3 by a slight pressure of the hand so as to throw the end-piece 9 into the horizontal position shown by the dotted lines in Figure 1.

5, as shown throughout the several views, is an approximately semi-circular metallic hood with extended ends placed upon the end-piece 9 and adapted to cover the end of the bobbin when the machine is in operation, without interfering with its revolution; while 8—8 represent the bobbins themselves. These bobbins 8—8 are retained or supported by a metallic bed bent or pressed into substantially V-shaped troughs, a cross-section of which is shown by 6—6' in Figure 2, and a plan view by the same numerals in Figure 4.

The smaller ends of the bobbins, as shown in Figures 3 and 4, are provided with the hoods 10, these hoods being held in place by being fixed upon the vertical member 16 which is itself secured to the adjusting strip 11 and the base board 1.

My adjusting device for different lengths of bobbin is disclosed best in Figures 3 and 4, 3 being a vertical view and 4 being a plan view thereof.

The base board 1 which supports the entire holder (excepting the hooded end covering the smaller end of the bobbins) is usually comprised of a wooden board running the entire length of the frame, while the hooded member 16—10 is secured to the adjusting strip 11, as shown best in Figure 3. The member 16 is bent at right angles and comprises the vertical portion 16 and the horizontal portion 13. This horizontal por-

tion 13 is fixed to the strip 11 by the screws 15 and is provided with a slot 17 and a set screw 12, as shown in Figure 4. This slotted member 16—13 is usually fastened to the strip 11 and the board 1 only at each end of the frame, although one or more intermediate slotted members 13 may be used in case of very long frames.

In practice, I find it more convenient to 10 make the holders in groups or sections of three or four, the various groups being separated from each other by a slight space, but the board 1 and the strip 11 is continuous throughout the entire length of the 15 frame and the slotted members 13 are fixed to the strip 11, only at the two extreme ends of the frame; or, where the frame is very long, at one or two intermediate points in addition.

20 When it is desired to use bobbins of a different length from those with which the holders are set, all that is necessary is to loosen the screw 12, separate the strip 11 the desired distance from the board 1, tighten 25 the screw 12, and the holder is thus adjusted for the new length of bobbin.

I am aware that prior to my invention, bobbin holders have been devised for securing the ends of the bobbins, but in all the 30 bobbins known to your petitioner, irregularities in the draft upon the thread will displace the locking member and allow the bobbin to be pulled from its bed, and where the draft upon the thread is not 35 wholly vertical, as is frequently the case, the lateral pull will also serve to displace the retaining devices now in use, and thus pull the bobbin from its bed. Such retaining devices as have come to the knowledge of 40 your petitioner are held in place by gravity alone, by having the point of support of said locking device slightly outside the point of contact with the bobbin. These holders are subject to the disadvantages above mentioned, particularly after they have been in 45 use for a considerable period.

By my device, no lateral pull or irregularity of draft can possibly pull the bobbin from its bed because the extended ends of 50 the hoods 5—10 are carried downward below the center of the bobbins while my locking device, shown in the Figures 1, 2 and 5 completely and effectually prevents accidental detachment by any draft that can possibly 55 be made upon the bobbin.

I am not aware that any device has been applied to a bobbin holder of the character described which will permit of quick adjustment for different lengths of bobbin, the 60 only device of this kind known to your petitioner being such as to require a separate unscrewing of a screw for each separate bobbin, or in some cases of two screws for every three or four bobbins, thus requiring 65 an unreasonable length of time for a frame

of fifty or more bobbins, whereas by my invention the loosening of two to four screws is all that is required for an entire frame holding from fifty to two hundred bobbins.

Having now described my invention, what 70 I claim and desire to secure by Letters Patent is:—

1. A bobbin holder comprising a plurality of troughs of V-shaped cross-section secured to a base; a series of opposed vertical end-pieces, those at one end of said bobbins being hinged to said base and adapted to swing outwardly away from the bobbins, and the end-pieces at the other end of said bobbins being fixed on a movable strip attached to 75 said base, said hinged end-pieces being each provided with a wing at right angles thereto, said wing having an enlarged or expanded lower edge; and a spring member fixed upon the base aforesaid and having a curved end adapted to engage said wing and to hold the attached end-pieces normally in a vertical position until purposely released by the operator, substantially as set forth. 80

2. In a bobbin holder of the type described, a base board carrying a series of V-shaped troughs; end-pieces at one end of said bobbins hinged to said base and provided with curved hoods for retaining said bobbins in their respective troughs and normally being in a vertical plane at right angles to said base; a locking device for holding said end-pieces in a normally vertical position; end-pieces at the opposite end of said bobbins, also provided with curved hoods; 90 said latter end-pieces being fixed upon a strip of wood or other material, which strip is capable of being adjusted at varying distances from the base board aforesaid so as to permit the use of bobbins of 95 different lengths, all as set forth. 100

3. In a bobbin holder of the type described, a base board carrying a series of V-shaped troughs; end-pieces at one end of said bobbins hinged to said base and provided with rigidly connected curved hoods for retaining said bobbins in their respective troughs and normally being in a vertical plane at right angles to said base; a locking device for holding said end-pieces in a normally vertical position; end-pieces at the opposite end of said bobbins, also provided with curved hoods; said latter end-pieces being fixed upon a strip of wood or other material, which strip is capable of being adjusted at varying distances 110 from the base board aforesaid, by means of the slotted plates and the screws, all substantially as described. 115

4. In a bobbin holder of the type described, a base, a series of troughs secured thereto, a plate pivotally connected to one end of said base capable of assuming either a vertical or a horizontal position, foot members rigidly carried by said plate, means for retaining said plate in its vertical position, 125 130

a strip associated with the opposite end of said base, an angular member rigidly connected to said strip and adjustably connected to said base, and hood members carried by 5 said angular member.

5. In a bobbin holder of the type described, a base, a series of troughs secured thereto adapted for supporting bobbins extending longitudinally of said base, an end 10 wall hingedly connected to said base adapted for assuming a horizontal position for al-

lowing said bobbins to be removed longitudinally from said troughs, and a wall at the opposite end of said base adjustably secured thereto for allowing bobbins of different 15 lengths to be supported in said troughs.

In testimony whereof I affix my signature in presence of two witnesses.

JOSEPH FOURNIER.
